WATCHMAN'S SERVICE SYSTEM

Norman H. Saunders, Homewood, and Morris E. Griffins, Western Springs, Ill., assignors to Associated Electric Laboratories, Inc., Chicago, Ill., a corporation of Delaware

Application September 23, 1936, Serial No. 102,103

12 Claims. (Cl. 179—5)

The present invention relates in general to watchmen's service systems, and more in particular to a watchman's service system which is auxiliary to or forms part of an automatic private branch exchange telephone system. The object 5 of the invention is to produce a new and improved watchman's system of this character.

The invention and the various features of improvement which it includes will be described 10 hereinafter with reference to the accompanying drawings, which show by means of conventional circuit diagrams the equipment by which the invention is carried out and also so much of the equipment of an automatic private branch exchange as is necessary to enable the invention 15 to be understood.

In the drawings

Fig. 1 shows an automatic telephone station 20 which may be a station of a private branch exchange.

Fig. 2 shows control apparatus for a particular route, and

Fig. 3 shows equipment at a supervisor's station.

Referring to the drawings, Fig. 1 shows at the left an automatic telephone station A, which is 25 a station of the private branch exchange. The exchange may be of nine-hundred line capacity, that is, there may be nine-hundred stations such 30 as station A. Each station has a line switch such as LS in which its line terminates at the automatic switchboard and which is used for outgoing calls.

Calls are completed by means of selectors and 35 connectors. The lineswitches such as LS may be divided into groups and each group has access to a group of selectors. The selectors have access in common to nine groups of connectors. One 40 of the selectors is shown at S, Fig. 1, but no connectors are shown as they are not involved in the invention.

The lineswitches may be of the well known 45 rotary type in which the wipers have no home position and move in a forward direction only. The selectors and connectors may be of the well known Strowger type.

The requisite number of telephone stations located at strategic points throughout the 50 premises served by the branch exchange are selected as watchmen's stations. There may be as many as sixty of these watchmen's stations according to the present disclosure, and since this is a much greater number of stations than can be taken care of by one watchman it will be assumed 55 that they are divided into three groups or routes, each handled by a different watchman. Station A is the No. 1 station on route 1, which includes a total of ten stations, although any single route may have as many as twenty-four stations.

For each route there is provided a control ap-

paratus. Fig. 2 shows the control apparatus for route 1, which comprises a timing switch TS, a station switch SS, and a checking switch CS, together with the relays and circuit connections shown. The three switches mentioned may be 5 ordinary twenty-five point rotary lineswitch mechanisms.

The stations selected as watchmen's stations differ from the rest of the telephone stations by having their test conductors in the exchange 10 connected to the banks of one of the station switches such as SS, Fig. 2. Explaining this briefly, it has been mentioned that station A is the No. 1 watchman's station on route 1. The test conductor 9 is therefore connected, by means 15 of a conductor 161, to the first contact in the bank of wiper 133 of station switch SS, Fig. 2, it being recalled that the control apparatus in Fig. 2 is the control apparatus for route 1. The test conductors of watchman's stations 2, 3, etc., 20 on route 1 are connected in regular order to the second, third, etc. contacts in the bank of wiper 133. Thus conductor 162 extends to the test conductor of station No. 2, while conductor 163 extends to the test conductor of station No. 3. 25 In order to avoid complicating the drawings, the complete circuit connections of only one station have been shown, but it is thought that the arrangement will be clearly understood from the foregoing. The stations on routes 2 and 3 are of 30 course connected up the same way, except that instead of being connected to the station switch in Fig. 2, the test conductors of the stations on routes 2 and 3 are connected to the station switches associated with the corresponding 35 routes.

When a watchman makes a report from a station he uses the automatic telephone at such station and the exchange switchboard to establish a connection with the control apparatus for 40 the particular route he is on and to which the reporting station belongs. In order to enable the proper route control apparatus to be selected from any station a plurality of route switches are provided. There may be two of these switches, 45 one of which is shown complete at RS, the other being indicated at RS'. These route switches are of the single motion rotary type. lineswitch mechanisms may be used; but are directly controlled and have access to the three control 50 apparatuses for the three routes. The first level of the banks of the selectors such as S may be used to give access to the route switches.

Common to all the routes is a recording device R indicated by the dotted rectangle in Fig. 2. 55 This recording device may be of the type shown in Sengebusch Patent No. 1,862,200, but other electrically operated recording devices could be used. The Sengebusch recording device comprises a row of sixty individual station magnets 60

and a parallel row of sixty type wheels, each of which bears the minutes designations from 1 to 60. There is also a common type wheel bearing the hours designations. Time controlled mechanism periodically advances the minutes wheels and the hours wheel to keep them set in accordance with the time of day. When any magnet is operated from the corresponding station, apparatus is set in motion which presses a chart 5 against the minutes wheel corresponding to the operated magnet, thereby printing the time in the correct station column on the chart. After each printing operation the chart is advanced, and once every hour the hours wheel is caused 10 to print. The complete recorder, therefore, affords means for making a time record on a single chart of reports from sixty stations.

chart of route 1 from any station. The ten stations on route 1 may be assigned to the first ten recording positions. To accomplish this the first ten contacts in the bank of wiper 134 of station switch SS, Fig. 2, are connected to the first ten magnets of the recorder. Fig. 2 shows four of these magnets and the circuit connections. If there are fifteen stations on route 2, these stations may be assigned to fifteen positions in the recorder beginning with position sixteen, leaving five vacant positions for growth in route 1; and the assignment is effected by connecting the first fifteen bank contacts in the bank of the wiper similar to 134 of the station switch of the route 2 control apparatus to fifteen consecutive magnets of the recorder, beginning with the sixteenth magnet. Assignment of the stations on route 3 is made in a similar manner.

35 The system contemplates that a head watchman or supervisor will be on duty during the hours when the watchmen are on their rounds, and the equipment shown in Fig. 3 is provided for the use of this supervisor. The supervisor's 40 telephone is shown at B, and is provided with a lineswitch LS' for making outgoing calls. OGK is a key for connecting up the lineswitch LS' and MK is a monitor key for communicating with a watchman when the watchman is reporting. 45 There are as many keys MK as there are route switches such as RS. TL is a trunk lamp associated with monitor key MK and individual to route switch RS. TL' is a second trunk lamp for the key MK' and the route switch RS'. GK is a 50 guard key for notifying reporting watchmen that the supervisor wants to communicate with them, and G is a guard lamp. The key GK and lamp G are common to the route switches. RL are route lamps, one for each route, and RA are route alarm 55 lamps. SL are station lamps, one for each station. These station lamps are preferably arranged in three rows, opposite the three route lamps and three route alarm lamps. LRK is a combined listening and ringing key. Associated 60 with this key is a trunk circuit and trunk line leading to a telephone C, which may be located at the nearest police station.

at the nearest police station.

The operation of the system will now be described, considering for this purpose the round of the watchman on route 1. It will be understood that the watchman visits the stations on his route in regular order, beginning with station #1, and reports in from each station. As each report is made the time is recorded on the recording device in the column corresponding to the reporting station and thus a complete record is made which can be checked at any time in order to determine if the watchman has performed his duties properly.

75 When the watchman arrives at station A,

which is the #1 station on route 1, he removes the receiver at the telephone and dials the necessary digits to establish a connection with the control apparatus for route 1, that is, the control apparatus shown in Fig. 2. This is all that the watchman has to do in order to report from the station. The digits which the watchman has to dial in this instance are the digits 1 and 1, that is, the watchman dials the number 11. He dials this same number from each station on his route. It may be stated here that the watchman on route 2 always dials the number 12, while the watchman on route 3 always dials the number 13.

On route 3 always dials the number 15.

Responsive to the removal of the receiver at station A, a bridge is closed across the line conductors 2 and 3, which energizes the line relay 3 of the lineswitch LS. On energizing, relay 3 closes a circuit for the switching relay 4 in series with the stepping magnet 8, and at the same time connects the test wiper 7 to the junction of the switching relay and stepping magnet. If at this time the wipers of the lineswitch are standing on a busy trunk line, the contact engaged by the test wiper 7 will have a ground potential on it and the switching relay 4 will be short circuited. This ground potential is also effective to energize the stepping magnet 8, advancing the switch wipers in search of an idle trunk line. In the present case it will be assumed that the selector S with which the wipers of the lineswitch LS are associated is idle, and consequently when the line relay 3 energizes the switching relay 4 energizes immediately thereafter, and extends the line conductors 2 and 3 through to the wipers 5 and 6 and thence to the line relay 15 of the selector S. The energization of the switching relay disconnects the line relay 3 but this relay is slow to fall back and holds up the switching relay 4 until ground is received back over the release trunk conductor 11. The switching relay 4 also establishes a connection between the test wiper 7 and the test conductor 9.

When the connection is extended to the selector S by the lineswitch LS, as above described, the line relay 15 is energized over the calling line and closes a circuit for the slow-acting release relay 16 at 30. On energizing, the latter relay grounds the release trunk conductor at 33 to establish a holding circuit for the switching relay 4 of lineswitch LS. Relay 16 also connects the test wiper 24 to the upper winding of the test relay 18 at 32 and prepares a circuit for the vertical magnet 20 at 31. Relay 17 is also energized at this time, by ground on the release trunk conductor 11, the circuit extending through the upper pair of off-normal springs ON. Ground on conductor 11 also energizes the lower or polarizing winding of the electropolarized test relay 18. 45 50 55

The watchman may now dial the first digit of the number 11, thereby interrupting the circuit of the line relay 15 a single time, and causing this relay to fall back once and transmit an impulse to the vertical magnet 20. Responding to this impulse, the vertical magnet raises the shaft carrying wipers 22-24 one step, so that the wipers stand opposite the first level of contacts in their banks. When the shaft is raised, the three sets of off-normal springs are shifted and at the upper set the circuit for the upper winding of relay 17 is broken. This relay does not fall back immediately, however, because it receives an impulse from the line relay 15 in parallel with the vertical magnet 20. A short interval after the switch has been stepped up by this impulse, relay 17 falls back, and the line relay 15 now being in energized

position, a circuit is closed for the rotary magnet 21. This circuit includes the lower pair of off-normal springs ON, which are now closed. Upon the closure of this circuit the rotary magnet begins to operate in the manner of a buzzer, as it interrupts its own circuit, and rotates the switch shaft carrying wipers 22-24 in search of an idle route switch, such as RS.

The idle condition of a route switch is indicated by the presence of a battery potential on the associated test conductor such as 41, and assuming that the route switch RS is idle, test conductor 41 will have a battery potential on it, the potential being derived by the normal connection of this conductor to the upper winding of relay 52. When the hunting selector S arrives at contacts 25-27, therefore, which are associated with the switch RS, the test wiper 24 will find a battery potential and the test relay 18 will be energized over its upper winding to ground on the release trunk conductor 11. On energizing, relay 18 connects the release trunk conductor 11 with the test wiper 24 at 28, opens the release magnet circuit at 29, and switches the incoming line conductors from the line relay 15 to the wipers 22 and 23. The line relay 15 accordingly falls back and breaks the circuit of the release relay 16, but this latter relay is slow acting and maintains ground on the release conductor 11 until a holding ground is fed back from the selected route switch RS. Relay 18 holds up by its lower winding alone.

When the route switch RS is selected as described in the foregoing, relay 52 is energized in series with relay 18, and after 18 has operated, relay 52 holds up by ground fed forward over 41. Also the line relay 50 is energized over the calling line and at 60 closes a circuit for the slow-acting relay 51. On energizing, relay 51 grounds the release trunk conductor 41 at 64, thereby completing a holding circuit for the selector S and lineswitch LS. In addition to the foregoing, relay 51 prepares locking circuits for relays 54 and 55 at 62, prepares an energizing circuit for relay 56 at 63, and prepares a stepping circuit for stepping magnet 57 at 65. It may be mentioned at this time that the line relay 50, on energizing, closes a circuit for the trunk lamp TL, Fig. 3, at 61. The lighting of this lamp indicates to the supervisor that a watchman is calling in on the first route switch RS.

The watchman may now dial the second digit in the number 11, with the result that the line relay 59 deenergizes once and transmits one impulse to the stepping magnet 57, the circuit extending from ground at 60 by way of 65, 67, and winding of 57 to battery. The stepping magnet 57 responds to this impulse by advancing wipers 85-88 one step, so that the wipers 85-87 establish connection over conductors 89-91 with the control apparatus in Fig. 2. When the wiper 88 leaves its normal position it breaks the circuit for the upper winding of relay 52, but this relay holds on momentarily due to receiving the stepping impulse in parallel with the magnet 57. When relay 52 falls back it breaks the stepping circuit at 67, and at 66 completes a circuit for the switching relay 56. The energizing circuit for the switching relay 56 extends from ground at 73 by way of contacts of switching relay 56' of route switch RS', contacts controlled by armature 79 of relay 56, lower winding of relay 56, 66, 63, 70, 73, and upper winding of relay 56 to battery. Relay 56 energizes over the above circuit and establishes a locking circuit for it-

self at 79. At 78 relay 56 breaks the chain circuit over which it was initially energized, and this prevents the energization of switching relay 56' in the other route switch, if another watchman should report in at this time. In addition to the above, relay 56 grounds wiper 85 at 76, prepares a circuit for relay 55 at 77, establishes a holding circuit for relay 51 at 80, and at 81 substitutes the booster battery 82 for the previously established ground connection to the release trunk conductor 41. The purpose of this latter operation will be explained presently. The object in closing the holding circuit for relay 51 is to hold up the connection and insure its being recorded in the event that the watchman should hang up his receiver prematurely.

The operation of the control apparatus in Fig. 2 may now be considered. When relay 56, Fig. 1, grounds wiper 85 at 76, a circuit is completed over conductor 89 for relay 100. A branch of this circuit extends to the route lamp RL for route 1 and lights the lamp to notify the supervisor that a report is being made from a station on route 1. On energizing, relay 100 closes a circuit for relay 101 at 112, and a circuit for test relay 102 at 111. Relay 102 is a quick acting relay, while relay 101 has a slug at its upper end and is slow to energize. Relay 102 is also a marginal relay and cannot operate from a grounded test conductor. That is, it is unable to energize when supplied with current from the exchange battery alone. At the present time, however, since the booster battery 82 has been connected up by relay 56, Fig. 1, and since the station switch SS is standing in first position, corresponding to the first watchman's station, the test relay 102 has a circuit which includes the exchange battery and the booster battery 82 in series, and it immediately energizes, opening the circuit for relay 101 at 117 before this relay can operate, and closing a locking circuit for itself at 116. The initial energizing circuit of relay 102 may be traced from ground by way of booster battery 82, the protective resistance associated with this battery, 81, 64, 41, 27, 24, 28, 11, 7, 10, 9, 161, 133 in first position, upper winding of relay 102, 115, 111, the exchange battery, and thence to ground.

The energization of relay 102 closes the recording circuit at 118. This circuit extends from ground by way of 118, 129, wiper 134 in first position, and thence through the first individual station recording magnet of the recorder R to battery. Responsive to the operation of this magnet the recorder prints the time in the column allocated to station #1 of the first route. The circuit of the recording magnet is only momentarily closed, as relay 105 is energized over a portion of the same circuit and opens the portion extending to the recorder at 129. Relay 105 also takes ground off the conductor 170 at 132, but this conductor remains grounded at 120 as long as relay 102 remains energized. Relay 105 also closes the circuit of relay 104 at 131.

Upon energizing, relay 104 prepares a circuit for the stepping magnet 137 at 128, opens the automatic homing circuit including the said magnet at 126, closes a circuit for relay 103 at 127, and grounds conductor 90 at 125. The circuit of relay 103 may be traced from ground by way of wiper 135 in first position, 127, and winding of relay 103 to battery. On energizing, relay 103 places ground on wiper 136 at 124, thereby lighting up the #1 station lamp SL in the row assigned to route 1. In addition to the foregoing, 75

relay 103 prepares a locking circuit for itself at 123 and completes a circuit for connecting stepping magnet 138 of the timer switch TS to the timer T, represented herein by a cam which is 5 assumed to be continuously rotating at the rate of one rotation per minute. The timer may be common to all the control apparatus of the several routes. The circuit for the stepping magnet 138 extends from ground by way of the contacts 10 of the timer, 121, 119, 130, and winding of magnet 138 to battery. This circuit is closed momentarily once every minute.

The effect of grounding conductor 90 at 125 of relay 104 will now be considered. A circuit is 15 completed for relay 55 which extends from ground by way of 125, 90, 86, 77, and winding of relay 55 to battery. On energizing, relay 55 locks itself at 71, closes a circuit for buzzer relay 53 at 72, and opens the circuit of relay 56 at 73. Relay 20 56 accordingly falls back and opens the holding circuit for the release relay 51 at 89. The circuit for the buzzer relay 53 extends from ground in Fig. 3 by way of normally closed contacts of key GK, conductor 93, 72, 68, and winding of 25 buzzer relay 53 to battery. Relay 53 interrupts its own circuit at 68 and produces a tone current which is transmitted through the small condenser to the lower side of the line incoming to the route switch RS. This gives the watchman, who 30 is waiting on the line with the receiver to his ear, a signal indicating that the recording apparatus has been operated, and the watchman accordingly hangs up the receiver at station 1 and proceeds on his way to station #2.

35 When the receiver is replaced at station A the line relay 50 falls back and opens the circuit of release relay 51. Relay 56 having deenergized as already explained, release relay 51 is able to deenergize and unlock relay 55, which falls back 40 and opens the buzzer circuit at 72. Relay 51 also closes a homing circuit which may be traced from ground at the lower make-before-break contacts of relay 56 by way of the strapped contacts in the bank of wiper 88, wiper 88, 64, off-normal contacts ON, interrupter contacts of stepping magnet 57, and winding of the said stepping magnet to battery. Magnet 57 is intermittently operated over the above self interrupted circuit and advances the wipers 85—88 step by step to 45 home position, where the circuit is broken at wiper 88 and at the off-normal contacts.

While the route switch RS is being restored to normal position, the release trunk conductor 41 remains grounded over wiper 88, but when the 55 switch reaches home position this ground is removed and since relay 51 has deenergized the release trunk conductor 41 will become ungrounded, which breaks the holding circuits for the selector S and the lineswitch LS. At the 60 selector S the switching relay 18 falls back and closes a circuit for the release magnet 19 over 29, 30, 31, and the second pair of off-normal springs ON. The release magnet restores the switch in the well known manner and its circuit is broken at the off-normal contacts when the 65 switch reaches normal position. At the lineswitch LS relay 4 falls back, but the wipers remain standing on the selector S. The falling back of relay 4 connects up the line relay 3, so 70 that another call can be made from station A.

Returning now to the control apparatus in Fig. 2, when relay 56, Fig. 1, falls back as previously explained, it takes ground off wiper 85 at 76, and thereby breaks the circuit of relay 100, also extinguishing the route lamp RL. Relay 100 ac-

cordingly falls back, breaks the circuit for the upper winding of relay 102 at 111, and opens the locking circuit including the lower winding of relay 102 at 112. Relay 102 accordingly deenergizes and breaks the original energizing circuit 5 of relay 105 at 118. Whether relay 105 falls back or not at this time depends on whether or not the timing switch TS has taken a step from normal position. Only a very short time, perhaps two seconds, has elapsed since the timing circuit 10 was closed at 121 by the energization of relay 103 and the chances are that the timing switch has not been advanced. Under these circumstances, relay 105 immediately falls back when its circuit is 15 broken at 118, with results which will be presently explained.

However, it may happen once in a while that the timer T will send an impulse to the stepping magnet 138 between the pulling up of relay 103 and the falling back of relay 102, and under 20 these circumstances the timing switch TS will have taken one step at the time relay 102 falls back and breaks the circuit of relay 105 at 118. Explaining the operation under this condition of affairs, relay 105 does not deenergize, but remains 25 locked up over a circuit which extends from ground by way of wiper 139 of TS, contact 129, and winding of relay 105 to battery. Relay 102 being deenergized and relay 105 being energized, a homing circuit is established for the timing 30 switch TS which extends from ground by way of wiper 139, interrupter contacts of stepping magnet 138, 119, 130, and winding of the stepping magnet 138 to battery. Magnet 138 operates over the above circuit to automatically advance 35 the wipers of the timing switch to normal position, where the circuit is broken at wiper 139 and the switch stops.

When wiper 139 arrives at home position, the locking circuit of relay 105 is broken and the relay deenergizes, breaking the circuit of relay 104 at 131 and closing at the same point a circuit for the stepping magnet 137 of the station switch SS. Relay 104 is slow to release and the stepping circuit for magnet 137 is maintained until relay 104 40 has had time to fall back. The impulse thus delivered to magnet 137 operates the magnet and upon its deenergization the wipers 133—136 are 45 moved from first to second position. When relay 104 deenergizes it opens the initial energizing 50 circuit of relay 103 at 127, but relay 103 is slow acting and holds on until the advance of the switch SS from first to second position establishes a locking circuit which may be traced from ground by way of wiper 135 in second position, bank strapping, 55 123, and winding of relay 103 to battery. Relay 103 holds up over this circuit until the watchman has called in from the last station on route 1.

The falling back of relay 105 and the continued 60 energization of relay 103 serve to connect the timer T with the stepping magnet 138 of the timer switch over an obvious circuit which includes contact 121 of relay 103 and the back contact 130 of relay 105. The advance of wiper 136 from first to second position extinguishes the #1 station lamp SL for route 1, and lights up the #2 station lamp. This indicates to the supervisor that the watchman on route 1 has left the #1 station 65 and is on his way to the #2 station.

Reviewing briefly the condition of the apparatus at this juncture, the station switch has been advanced from position 1 to position 2, so that the test relay 102 has been connected through wiper 133 with conductor 162, which extends to and connects with the test conductor of station #2. Thus 70 75

a circuit has been prepared so that the test relay 102 can respond when the report is made by the watchman from the #2 station. The #2 lamp SL for route 1 has been lighted over wiper 136 so that 5 the supervisor knows that the watchman is on his way to the #2 station on his route. Also the timing switch TS is advancing at the rate of one step per minute. The primary purpose of this timing switch is to light the route alarm lamp RA for 10 route 1 in case the watchman fails to report at any station on time. The time allowed for the watchman to go from one station to the next is variable within certain limits, but as disclosed herein the time is about ten minutes, as the conductor 171 15 over which the alarm is brought in is connected to the tenth contact of the bank of wiper 140. Obviously the time could be changed by shifting this conductor to a different contact.

In order to explain the function of the timing switch more fully, it will be assumed now that the 20 watchman fails to report from the #2 station within the time allowed. After ten steps have been taken by the timing switch TS, a circuit is completed for relay 110, the circuit extending 25 from ground at 132 by way of wiper 140, conductor 171, and winding of relay 110 to battery. On energizing, relay 110 locks itself at 157, prepares a circuit for the ringing relay 203 at 158, and closes a circuit for the route alarm lamp RA of route 1 at 30 159. The lighting of the route alarm lamp notifies the supervisor of the fact that the watchman on route 1 has failed to report at some station within the proper time, and glancing at the station lamps SL the supervisor sees at once that the station 35 at which the watchman is overdue is station #2.

The supervisor may now follow any one of several courses. As the watchman's rounds are preferably staggered as to time, the watchmen for routes 2 and 3, or one of them, may be at the 40 supervisor's office where the watchmen spend their time when they are not actually travelling on their rounds. If another watchman is present, therefore, the supervisor will generally send him out to investigate.

45 In the event that none of the other watchmen are around, the supervisor may call one of them by operating the guard key GK, Fig. 3. The guard key GK is common to both of the route switches RS and RS' and when it is operated ground is removed from conductor 93 and the corresponding conductor extending to the other route switch. It follows from this that the 50 next watchman to report fails to obtain a signal by the operation of the buzzer such as 53 and he will wait until the supervisor can talk to him.

Assume for instance, that the watchman on route #2 calls in from some station on his route and seizes the route switch RS. Having 55 dialled the number by which the report is effected, the watchman will listen in the receiver for the signal which notifies him that recording has taken place and that he is free to proceed to the next station. As explained hereinbefore this signal is produced by the energization of relay 55, which closes a circuit for the buzzer relay 53 at 72. Under the present conditions, however, the circuit of the buzzer relay 53 cannot be closed because it has been opened at the key GK. The supervisor knows that the watchman 60 has completed dialling because of the lighting of the guard lamp G, which is brought in by the closure of its circuit at 75, and he knows that the watchman is using the route switch RS because of the lighting of the trunk lamp TL, rather than TL', and accordingly he actuates 65

key MK in order to establish a connection between his telephone line 206-207 and the line incoming to the route switch RS. After removing the receiver at telephone B the supervisor is now able to talk to the waiting watchman and give him instructions with regard to investigating the reason for the failure of the watchman on route 1 to report at station #2. 5

It will be assumed now that either with or without the assistance of the second watchman, 10 the watchman on route 1 arrives at station #2 and reports in.

The number 11 is dialled as previously explained, and the switches are operated in the same manner, connection being established from 15 the #2 station over its associated lineswitch such as LS, the selector S or a similar selector, and one of the route switches, the route switch RS, for instance. The control apparatus in Fig. 2 operates in the same manner as previously 20 described. Relay 100 energizes, followed by the energization of relay 102. The energization of relay 102 is followed by the operation of the recorder R and an instant later relay 105 operates. Relay 105 operates relay 134, which 25 grounds conductor 90 and energizes relay 55 to close the buzzer circuit and break the circuit of relay 56. If the supervisor has restored key GK 30 the watchman will receive a signal in the usual manner and will hang up the receiver and proceed to the next station. In this case, however, the supervisor will probably have left the key GK in operated position so that the watchman will be sure not to leave the #2 station before the supervisor can talk to him. The automatic 35 switches in use by the watchmen for reporting, of course, do not release until the watchman hangs up the receiver. After receiving the watchman's explanation, the supervisor may restore the key GK and also the key such as MK 40 which was used for establishing the talking connection. The watchman hangs up and proceeds to the next station.

When the relay 56 in Fig. 1 deenergizes, it 45 allows relays 100 and 102, Fig. 3, to be deenergized, and the falling back of the latter relay breaks the locking circuit of relay 110, relay 105 being still in operated position. Relay 110 accordingly falls back and extinguishes the route alarm lamp RA of route 1. Relay 102 also breaks 50 the initial energizing circuit of relay 105, but this relay remains locked up over wiper 139 of the timing switch until the timing switch has been restored to normal. The restoration of the timing switch to normal takes place immediately 55 following the deenergization of relay 102, as previously explained. When the timing switch reaches normal position relay 105 is unlocked and deenergizes, breaking the circuit of relay 104. Relays 105 and 104 now transmit an impulse to 60 stepping magnet 137 of the station switch SS, which responds to the impulse by advancing the wipers 133-136 to third position. The movement of the wiper 133 from second to third position prepares the circuit of the test relay 102 by 65 way of conductor 163, which is connected to the test conductor of the #3 station. The movement of wiper 136 from second to third position extinguishes the #2 station lamp SL on route 1 and lights the #3 station lamp. 70

Reverting now to the point where the watchman on the #1 route failed to report in at the #2 station within the allotted time, it will be assumed that no watchman is available to send out to investigate, and it will be assumed fur- 75

ther that the routes are so far apart that it is not practicable to call a watchman from one of the other routes to investigate the trouble on route #1. In these circumstances the supervisor 5 will usually deem it necessary to go himself to investigate the trouble. Before leaving, however, he may call the police station at which telephone C is located, which is done by removing the receiver from the telephone B and operating the 10 key LRK first to ringing position and then to listening position. When the key LRK is moved to ringing position, or to the right as it is shown in the drawings, ground is placed on conductor 205 of the trunk extending to the police station 15 and at the same time the generator GEN is connected to the other conductor 204. This rings the bell at telephone C. When the key LRK is thrown to the left, the line conductors 206 and 207 are extended through to the impedance coil 200, and at the same time a circuit is closed for 20 relay 202. This relay, on energizing, connects the trunk conductors 204 and 205 with the impedance coil 201. The telephones B and C are then supplied with talking battery through 25 impedance coils 200 and 201, respectively, and since the coils are connected by means of condensers, a talking circuit will be established, over which the supervisor can talk to the officer in charge at the police station. The supervisor may inform 30 the officer of the possibility of trouble so that preparations can be made to send assistance if it should be required. After the conversation is finished the supervisor hangs up the receiver at telephone B, restores key LRK, and proceeds with 35 his investigation, leaving the office temporarily unattended.

It will be assumed now that the watchman has merely been delayed for some reason or other, perhaps he has stopped to investigate some noise 40 that turns out to be a false alarm. Accordingly the supervisor will send him on to report from station #2 and will return to his office. On reaching the office the supervisor may call up the police station in the manner previously described 45 and notify them that no assistance is required.

It may happen, however, that the supervisor will run into some real trouble, making it impossible for him to return to his office. After about 50 ten minutes has elapsed, as determined by the timing switch TS, a circuit is completed for the ringing relay 203. This circuit may be traced from ground at 132 by way of wiper 140, conductor 172, 158, 212, and winding of relay 203 to battery. Relay 203 locks itself over conductor 211 to ground 55 at 132 and closes a ringing circuit over the trunk line 204—205 at 215 and 216. The completion of this ringing circuit rings the bell at telephone C continuously. Knowing from this that the supervisor is in trouble, the police station will send 60 assistance immediately. The bell continues to ring until order is restored and the proper report is made from the #2 station, whereupon relay 110 is unlocked as previously described to extinguish the route alarm lamp, and at the same time relay 203 is unlocked to break the ringing circuit over 65 the line of telephone C.

The operation of the checking switch CS, Fig. 2, 70 will now be explained. For this purpose it may be assumed that the station switch SS is in the third position, the #3 station lamp SL for route 1 is lighted, and the watchman on route 1 is presumably on his way from station #2 to station #3. It will be assumed now that instead of reporting 75 from station #3 the watchman skips this station and reports in from station #4. Under these cir-

cumstances the checking switch CS is operated with results which will be pointed out.

It will be assumed that the watchman reports in by means of a lineswitch similar to lineswitch LS, the selector S, and the route switch RS. 5 When relay 56 in the route switch RS operates and grounds wiper 85, a circuit is completed for relay 100 in the manner already described. Relay 100 connects the exchange battery to the upper winding of relay 102 at 111, and at 112 closes a 10 circuit for the slow-to-energize relay 101. Relay 102 fails to operate now because the station switch SS is standing in third position, whereas the 15 watchman is reporting from the #4 station, and the booster battery 82 will be connected by way of the test conductor of the fourth station to conductor 164, connected to the fourth contact in the bank of wiper 133. Consequently the test circuit will be open at the bank of wiper 133 and test relay 102 will fail to operate, as stated. After an 20 instant relay 101 operates, since its circuit is not opened at 117, and transfers the exchange battery testing connection to the relay 109 at 115. In addition, relay 101 closes an operating circuit for the stepping magnet 160 of the checking switch 25 CS, said circuit extending from ground at 132 by way of 113, conductor 173, interrupter contacts of the stepping magnet 160, and the winding of the stepping magnet to battery. The above circuit is interrupted by the stepping magnet 160 each time 30 it energizes and accordingly the checking switch CS is advanced step by step in search of the reporting station.

When wiper 141 reaches the fourth contact in its bank it will pick up the booster battery potential on conductor 164, thereby energizing test relay 109. Relay 109 locks itself to grounded conductor 173 at 150, and at 151 closes a shunt around the interrupter contacts of the stepping magnet 160, which holds the magnet energized 40 and prevents further stepping of the switch. In addition to the foregoing, relay 109 grounds wiper 144 at 154, thereby lighting the #4 station lamp SL on route 1, and also closes a circuit for the route alarm lamp RA for route 1 at 156. Finally, 45 relay 109 closes the recording circuit at 152 and 153. This circuit extends from ground by way of 153, 147, 152, wiper 142, and the fourth individual station magnet of the recorder to battery. The recorder is operated to record the time in the 50 usual way. Relay 108 is operated over a portion of the recording circuit after an instant and opens the circuit at 147. Relay 108 also closes a circuit for relay 107, but this relay is slow to energize and a momentary ground is therefore applied to 55 conductor 91.

Responsive to the grounding of conductor 91, relay 54, Fig. 1, energizes over a circuit which extends from ground by way of 148, 149, 91, 87, and winding of relay 54 to battery. On energizing, relay 54 locks itself at 69 and opens the circuit of relay 55 at 70. It will be noted that relay 54 does not close a circuit for the buzzer relay 53 and consequently no signal will be heard by the watchman. 65

At the office the supervisor sees the lighted route alarm lamp RA associated with route #1, and since the #3 station lamp and also the #4 station lamp are lighted, the supervisor will know why the route alarm lamp has been brought in. 70 That is, he will know that this is not due to a delayed report but is due to reporting in from the #4 station instead of from the #3 station. The supervisor also knows by the lighted trunk lamp TL that the watchman is using the route switch 75

RS and accordingly he will throw the monitoring key MK to talk to him. Preferably the watchman will be advised that he has reported in from the wrong station and will be instructed to go back 5 and report from station #3.

The release of relay 56 responsive to the energizing of relay 55 of course unlocks the release relay 51 so that the switching equipment will be released when the watchman hangs up. Relay 10 56 falling back also ungrounds wiper 85 and breaks the circuit of relay 100. Relay 100 accordingly falls back and breaks the circuit of relay 101, which deenergizes and opens contacts 112. Conductor 173 remains grounded, however, over 15 contacts 155 of relay 109 and relay 109 remains locked up. This keeps the #4 station lamp and the route alarm lamp lighted while the watchman is on the way back to the #3 station.

When the watchman eventually reports in 20 from the #3 station, relay 100 is energized and its energization will now be followed by the energization of relay 102 in the normal manner. The various results that ensue from the operation of relay 102 have been fully explained and 25 consequently need not be gone over again. It may be stated, however, that when relay 102 falls back, ground is removed from conductor 170 at 120 and is not replaced until relay 105 falls back. As a result of the ungrounding of conductor 170 relay 109 becomes unlocked and the stepping magnet 160 is deenergized. The switch CS is not of the homing type and the wipers remain standing where they were. The falling back of relay 109, of course, puts out the route 30 alarm lamp and ungrounds the wiper 144 over which the #4 station lamp has been lighted. However, this #4 lamp is maintained in lighted condition due to the advance of the station switch SS from third position to fourth position. It will 35 be apparent that if the watchman had called from the #6 station, for example, instead of from the #4 station, then the corresponding lamp, brought in through the medium of the checking switch CS, would now be extinguished.

40 Continuing with the regular operation of the system, it will be assumed that the watchman reports from the remaining stations in regular order. The station switch SS is stepped ahead each time that a report is made, and following the report from station #10 will be stepped to the eleventh position. The advance of wiper 135 from position 10 to position 11 breaks the locking circuit of relay 103 and this relay accordingly falls back. On deenergizing, relay 103 closes a circuit for the stepping magnet 137 which extends from ground by way of wiper 135 in eleventh position, 122, 126, interrupter contacts of the stepping magnet 137, and winding of said magnet to battery. The magnet 137 energizes over this 45 circuit, breaks the circuit, and on falling back advances the station switch SS from eleventh to twelfth position. In the twelfth position of wiper 135 a circuit is completed for magnet 137 which extends from ground by way of wiper 135 in 50 twelfth position, 123, 126, interrupter contacts of stepping magnet 137, and winding of said magnet to battery. The stepping magnet 137 operates automatically over the last mentioned circuit until switch SS is advanced to position 1, where 55 the circuit is broken at wiper 135. This restores the equipment to its normal position, where it stays until the watchman goes over his route again and reports in from station #1.

An explanation will now be made of the operation and function of relay 106, Fig. 2, which is 75

associated with the checking switch CS. The purpose of this relay is to prevent the tying up of a route switch such as RS if the test relays 102 and 109 fail to operate for some reason. A possible cause for the failure of these test relays to operate is the disabling of the booster battery 82, perhaps due to the blowing of its fuse.

When the watchman endeavors to make a report under the conditions assumed in the preceding paragraph, relay 102 fails to operate following the operation of relay 100, and relay 101 operates to transfer the test circuit to test relay 109 and to start the operation of the checking switch CS. Under the assumed condition the test relay 109 will not be able to operate, and consequently the checking switch CS will continue to run and on passing through its twenty-fifth position will complete a circuit for relay 106. This circuit extends from ground by way of 114, wiper 143 in twenty-fifth position, and winding of relay 106 to battery. On energizing, relay 106 locks itself at 145, so that it remains energized after the wiper 143 has passed along, and at 146 prepares a circuit for grounding conductor 91. Since the checking switch CS is started from some random position, it may not have tested all of the stations on passing its twenty-fifth position, but it completes the test on the second rotation, and since the test relay 109 is still unable to pull up, the switch eventually passes through 30 its twenty-fourth position again, whereupon a circuit is completed for relay 54. This circuit extends from ground by way of 114, wiper 143 in twenty-fourth position, 145, 149, 91, 81, and winding of relay 54 to battery. On energizing, relay 35 54 breaks the circuit of relay 56, which falls back and breaks the circuit of relay 100. The deenergization of this relay brings about the deenergization of relay 101, which is followed by the stopping of the checking switch CS and the deenergization of relay 106, as will be readily understood.

The deenergization of relay 56 opens the holding circuit of relay 51 and leaves the route switch under the control of the watchman. The watchman has heard no signal and consequently he will think at first that the supervisor wants to talk to him and will wait on the line. Not hearing the supervisor come in the watchman will soon realize that something is wrong and will call the supervisor in the usual way through the automatic switching equipment of the branch exchange. When such a call comes in to the supervisor, the ringer 220 is operated and the supervisor answers the call by throwing the key OGK and removing the receiver at telephone B. The watchman is thus able to notify the supervisor that he is unable to obtain a signal responsive to reporting in from a station and the supervisor will investigate and see what the trouble is.

The invention having been described, that which is believed to be new and for which the protection of Letters Patent is desired will be pointed out in the appended claims.

What is claimed is:

1. In a watchman's system, a plurality of telephones used as reporting stations, common control apparatus including a station switch, means for maintaining said switch connected only to the station from which the next report is to be made, a recorder, means including said switch and an individual station circuit connection for controlling said recorder to record the next report when received, and means for automatically 70 controlling said recorder to stop recording when the next report is received, and means for automatically 75

advancing said station switch to prepare for the next report.

2. In a watchman's system, a plurality of telephones of an exchange serving as watchmen's reporting stations, test conductors for each of said stations, control apparatus including a station switch, a test circuit including said switch and successive ones of said test conductors, means including the exchange equipment for enabling the watchman at any reporting station to gain access to said control apparatus and close said test circuit, means controlled over the test circuit for recording the report, and means for automatically advancing said station switch to include a different test conductor in the test circuit after each report is made.

3. In a watchman's system, a plurality of automatic telephones serving as watchmen's reporting stations, said reporting stations being located on a plurality of different routes, a plurality of route switches, automatic switching equipment through which any reporting station may gain access to an idle route switch, an individual control apparatus for each route, means whereby the watchman at any reporting station, having gained access to a route switch, may directly control the same to establish connection with the particular control apparatus which is individual to the route on which the reporting station is located, and means for recording the time the connection is established.

4. In a watchman's system, a plurality of watchmen's reporting stations, control apparatus common to said stations and adapted to receive and record reports from such stations only in a particular order, other common control apparatus adapted to receive and record reports in random order, and means whereby said second mentioned apparatus is enabled to respond to a report only if such report cannot be received by said first mentioned control apparatus.

5. In a watchman's system, a plurality of watchmen's reporting stations, control apparatus common to a plurality of reporting stations and adapted to receive and record reports from such stations only in a particular order, other common control apparatus adapted to receive and record reports that cannot be received by said first mentioned apparatus, and means for actuating an alarm each time the second mentioned control apparatus is brought into use to receive and record a report.

6. In a watchman's system, a plurality of telephones of an exchange serving as reporting stations, common control apparatus for receiving and recording reports from said stations, means whereby said apparatus is enabled to receive a report at any given time from only a particular station, means including the exchange equipment whereby a connection can be extended by the watchman from any reporting station to said control apparatus, and means for transmitting a signal to the watchman only if the connection has been extended from the particular station from which the control apparatus is adapted to receive a report at that time.

7. A system according to claim 6, characterized by the provision of means under control of a supervisor for preventing a signal being transmitted to a reporting watchman for the purpose of inducing the watchman to wait at the reporting station, and means whereby the supervisor

can complete a talking connection with the reporting station.

8. In a watchman's system which comprises a plurality of routes, with a plurality of reporting stations on each route, supervisor's equipment including an individual station lamp for each station on each route, said station lamps being grouped in accordance with the routes to which the associated stations belong, means for maintaining a station lamp in each group lighted to indicate the station from which the next report is to be received, and means responsive when any report is received for lighting the route lamp of the route to which the reporting station belongs.

9. In a watchman's system, a plurality of telephones of an automatic exchange used as reporting stations, common control and recording apparatus, means including equipment of the automatic exchange whereby the watchman may gain access to said common apparatus to record a report from any station, means for preventing the release of said exchange equipment while the report is being recorded, and means effective after an interval in case the control apparatus fails to function for rendering said release preventing means inoperative, whereby the watchman is enabled to restore said equipment.

10. In a watchman's system, a plurality of telephones of an automatic exchange used as reporting stations, common control and recording apparatus including a test relay for controlling the recorder and means for preselecting the test conductor of the next station due to report, means including part of the automatic exchange equipment for extending a connection from such station to said common apparatus, a holding circuit for the operated exchange equipment, a booster battery, and means responsive to the establishment of the said connection for closing a circuit for said relay which includes said booster battery, said holding circuit, a part of the pre-selected test conductor, the said relay, and the exchange battery in series with said booster battery.

11. In a watchman's system, a plurality of telephones used as reporting stations, common control apparatus including a switch, a conductor for each of said stations terminating in said switch in a predetermined order, a test circuit including said switch, means controlled over said test circuit and one of said conductors responsive to a call from one of said stations for recording that call and for operating said switch to connect with the conductor of the next station, and means responsive to calls from successive stations for controlling said switch to successively connect the conductors of reporting stations to said test circuit in the predetermined order.

12. In a combined telephone and watchman's service system, a plurality of telephones of a telephone exchange serving as watchmen's reporting stations, a central office, means operable by the watchmen at said stations for extending talking connections therefrom to said central office in a definite order, means at said central office for notifying the watchman that his call has been registered at the central office, and means at said central office for preventing the watchman from receiving such notification when the connection is extended from a station not in the prescribed order.
